US00D818964S

(12) **United States Design Patent** (10) **Patent No.:** **US D818,964 S**
Corona (45) **Date of Patent:** **** May 29, 2018**

(54) **FEMALE ELECTRICAL CONNECTOR WITH LOCKING ARMS**

(71) Applicant: **DSM&T Company, Inc.**, Fontana, CA (US)

(72) Inventor: **Sergio Corona**, Upland, CA (US)

(73) Assignee: **DSM&T Company, Inc.**, Fontana, CA (US)

(**) Term: **15 Years**

(21) Appl. No.: **29/598,112**

(22) Filed: **Mar. 23, 2017**

(51) **LOC (11) Cl.** **13-03**

(52) **U.S. Cl.**

USPC **D13/146; D13/149**

(57) **CLAIM**

The ornamental design for a female electrical connector with locking arms, as shown and described.

DESCRIPTION

FIG. 1 is a top, front, right side perspective view of my new design of a female electrical connector with locking arms.

FIG. 2 is a right side elevational view thereof.

FIG. 3 is a left side elevational view thereof.

FIG. 4 is a top plan view thereof.

FIG. 5 is a bottom plan view thereof.

FIG. 6 is a front side elevational view thereof; and,

FIG. 7 is a rear side elevational view thereof.

The broken lines in FIGS. 1, 6 and 7 represent environment only, and form no part of the claimed design.

1 Claim, 2 Drawing Sheets
